UNITED STATES PATENT OFFICE

ALBION S. LANG, OF ROSLINDALE, MASSACHUSETTS

SAXOPHONE CORD

Application filed November 26, 1929. Serial No. 409,829.

This invention relates to a saxophone cord such as is used by saxophone players to support the weight of the saxophone while it is being played and particularly to a means for adjusting the length of the saxophone cord and retaining the adjusted length, and it has for an object to provide a novel construction for effecting and maintaining such adjustment which is simple and inexpensive to manufacture.

10 The saxophone cord herein shown is of that familiar type which comprises a length of cord arranged in two loops, one of which is a double loop, and which has a slide or adjusting member at the junction of the loops through which the cord passes, the arrangement being such that by shifting the position of the adjusting member on the cord the effective length of the latter may be changed.

20 The adjusting member of this invention is preferably made of wire which is bent so as to present a plurality of loops through which the cord is threaded, means being provided for anchoring the cord at one point to the adjusting member so that while the member may be adjusted to change the effective length of the cord yet after it is adjusted the cord will be firmly held from slipping through the member and thus the adjusted length will be maintained.

25 In order to give an understanding of the invention I have illustrated in the drawings some selected embodiments thereof which will now be described after which the novel features will be pointed out in the appended claims.

30 Fig. 1 is a perspective view of a saxophone player illustrating the use of my improved saxophone cord;

35 Fig. 2 is an enlarged perspective view of the cord showing one embodiment of the invention;

40 Fig. 3 is a still larger fragmentary view 45 of the adjusting member showing the way

in which the cord is threaded therethrough; Fig. 4 is a similar view showing a different embodiment of the invention;

Fig. 5 is a side view of the adjusting member shown in Fig. 3;

50 Fig. 6 is a view similar to Fig. 3 but showing still a different embodiment of the invention;

55 Figs. 7 and 8 are views similar to Fig. 3 but showing yet other embodiments of the invention.

60 In the drawings 1 indicates a saxophone player who is illustrated as playing a saxophone 2. 3 indicates generally the saxophone cord or support which encircles the neck of the player and is provided at its lower end with the usual hook 4 adapted to hook into an eye 5 with which the saxophone 2 is provided, all as usual in devices of this type.

65 The cord 3 is of that type which is provided with the upper loop portion 6 that encircles the neck of the wearer, and the lower loop portion 7 which is threaded through the eye 8 of the hook 4. The lower 70 loop 7 is a double loop, that is, each side of the loop comprises two strands of the cord 3, while the upper loop 6 is a single loop, each side thereof being formed by a single strand of the cord 3. The two sides of the upper loop are indicated at 9 and 10 respectively and this loop is shown as formed partially by a strap 11 to which the leads 9 and 10 of the cord are secured and which encircles the neck of the player. The strap 75 11 is not necessary, however, as the upper loop 6 might be completely formed of the cord 3.

80 The two strands of the cord forming one side of the lower loop are indicated at 12 and those forming the other side of said loop are indicated at 13.

85 The adjusting member embodying the present invention is preferably made from a length of wire which is bent into a shape to 90

present two loops or eyes, one to receive each of the sides 9 and 10 of the upper loop 6 and either a larger loop or eye to receive both of the strands 9 and 10, or two smaller loops to receive the strands independently, the cord forming the side 12 of the double loop 7 being firmly anchored or secured to the adjusting member.

In the embodiment shown in Fig. 3 the 10 adjusting member, which is indicated generally at 14, is made of a piece of wire which is bent to form the two eyes 15 and 16 each adapted to receive one of the sides 9 and 10 of the cord 3, and the larger loop or eye 17 15 adapted to receive both of said strands or sides 9 and 10 and in addition an anchoring loop 18 to which the two sides 12 of the double loop are firmly anchored.

The two sides of the upper loop 3, which 20 are indicated at 9 and 10, pass through the two eyes 15 and 16 respectively and then both pass through the eye 17. The two sides of the cord then merge into the lower loop and become the double side 13 of said 25 loop, both cords passing through the eye 8 of the hook 4 and then back to the adjusting member 14, the length of the cords between the eye 8 and the member 14 constituting the double side 12 of the lower loop. 30 This double side 12 of the lower loop is firmly anchored to the adjusting member 14 and in Fig. 3 this is accomplished by reason of the fact that the cord passes through the loop 18 and the two portions 12 of the cord 35 are firmly secured together adjacent the loop 18 by means of some clamping member 19. This clamping member may be in the form of a staple which encircles the two portions 12 and is clinched firmly about 40 them.

The loop or eye 18 is shown as standing at right angles to the loop or eye 17 and with this arrangement the four lengths of the cord constituting the two sides of the 45 lower loop 7 will lie in the same plane as indicated in Fig. 3 so that when the cord is worn the cords will lie flatly against the body.

The length of the cord may be adjusted by 50 holding the hook 4 with one hand and sliding the adjusting member 14 up or down with the other hand while the cord is slack. When the adjustment has been made and the cord is in use and is sustaining the 55 weight of the saxophone the friction of the cord through the eyes 15, 16 and 17 is sufficient to prevent the adjusting member from shifting its position so that the cord will maintain its adjusted length. Because the 60 portions 12 constituting one side of the double loop 7 are firmly anchored to the member 14 there can be no creeping of the cord through the loop 18 and consequently no loss of adjustment.

65 In Fig. 4 I have shown a slightly dif-

ferent embodiment of the invention which has the same characteristics as the embodiment shown in Fig. 3 but which is of slightly different shape. In this embodiment the wire from which the slide is made is bent to form the two loops 15 and 16 as above described and then is bent to form the larger loop 17a having the double lobe shape, the wire also being bent to form the loop 18 which occupies a plane at right angles to the loop or eye 17a.

In Fig. 7 I have shown a still different embodiment of the invention in which the lower eye of the adjusting member to which the sides 12 of the double loop are fastened is located in the same plane as the other eyes. In this embodiment said lower eye is indicated at 18a and the cord is anchored to the slide by being knotted thereto with a slip knot effect as shown.

In Fig. 6 I have shown still a different embodiment of the invention wherein the sides 12 of the double loop 7 are anchored directly to the loop 17. This is accomplished by the cord passing through said loop and by having the two sides of the cord tied or anchored together by means of a clamp 19.

In Fig. 8 I have shown still a different embodiment of the invention in which the wire from which the adjusting member is made is bent centrally to form the attaching loop 18c and to form the upstanding stem portion 21. Each end of the wire is bent to form an upper and a lower loop or eye, the upper loops being indicated at 15c, 16c and the lower loops at 23, 24. In this embodiment one side 9 of the cord passes through the eye or loop 15c and thence through the eye 23 while the outer side 10 passes through the eyes or loops 16c and 24. The two strands 12 of the lower loop 7 of the cord are anchored to the attaching eye or loop 18c by both passing through said loop. This may conveniently be done by 110 looping the cord about the back of the stem 21 and then having both strands 12 pass through the attaching eye 18c. This makes a convenient and yet neat anchorage.

I claim.

1. The combination with a saxophone cord presenting two loops, one of which is a single loop and the other of which is a double loop, of an adjusting member by which the length of the cord may be adjusted, said adjusting member being formed of a wire bent to present a plurality of eyes or loops through which the sides of the single loop portion of the cord are threaded and also bent to present an anchoring loop to which one end of the double loop portion of the cord is anchored.

2. The combination with a saxophone cord presenting two loops, one of which is a single loop and the other of which is a

double loop, of an adjusting member by which the length of the cord may be adjusted; said adjusting member being formed of a wire bent to present a plurality of eyes or loops through which the sides of the single loop portion of the cord are threaded and also bent to present a plurality of eyes or loops through certain of which the sides of the single loop portion of the cord are threaded and to one of which the end of the double loop portion is anchored.

In testimony whereof, I have signed my name to this specification.

ALBION S. LANG.
